UNITED STATES PATENT OFFICE.

EDWARD M. HEWLETT, OF SCHENECTADY, NEW YORK, ASSIGNOR TO GENERAL ELECTRIC COMPANY, A CORPORATION OF NEW YORK.

PROTECTIVE DEVICE.

1,291,512.

Specification of Letters Patent. Patented Jan. 14, 1919.

Application filed August 7, 1913. Serial No. 783,460.

To all whom it may concern:

Be it known that I, EDWARD M. HEWLETT, a citizen of the United States, residing at Schenectady, county of Schenectady, State of New York, have invented certain new and useful Improvements in Protective Devices, of which the following is a specification.

My invention relates to devices, such as relays and similar devices, which operate in response to currents dependent upon conditions in an electric circuit, and it relates especially to time limit protective devices which respond to abnormal conditions on an electric circuit with a certain amount of delay or time lag.

Many devices used in electrical distribution depend for their operation upon currents which vary with and are dependent upon conditions in an electric circuit. The proper operation of such devices requires that the current supplied to them shall be dependent upon conditions in the electric circuit, yet at the same time the operation of the devices may become unsatisfactory if the current supplied to them exceeds certain definite limits. For example,—many of the protective devices now used for opening a circuit in case of overloads and similar abnormal conditions, and particularly the usual types of time limit devices, are unduly affected and even temporarily deranged by very severe overloads and short circuits, which cause them to act practically regardless of the time limit for which they are set. This effect is particularly disadvantageous where a number of protective devices respond to the same abnormal condition and should normally trip out in a definite and unvarying sequence. In such a case a very heavy overload, such as a short circuit, may so affect the protective devices that they will all operate at practically the same time, or they may even operate in the wrong sequence.

The object of my invention is to render more reliable and certain the operation of devices which respond to currents dependent upon conditions in an electric circuit, and which become erratic and unsatisfactory in operation when subjected to currents in excess of certain limits. A further object of my invention is to render protective devices, especially time limit protective devices, more reliable and certain in action,

especially when very severe overloads, 55 short circuits and similar extreme conditions are present upon the circuit, and in general to improve the construction and operation of devices of this character. To this end I provide means for so modifying or controlling 60 the effect of an overload or other extreme condition upon the device responsive to the current dependent upon that condition that the device retains its characteristics and mode of operation in spite of the extreme 65 conditions upon the circuit. For example, the effect of an overload upon the overload relay is automatically modified or controlled to preserve the time limit or other characteristics of the relay whenever the overload 70 is so great that unless some suitable provision is made the time limit of the relay, for example, will be seriously changed. I prefer to obtain the desired result by some means which acts somewhat like a kind of 75 by-pass or safety valve for automatically diverting from the current carrying parts of the device the excess current resulting from the extreme condition, such as a severe overload on the electric circuit, and in this way 80 I shield or protect the device from the excess current which would otherwise interfere with the operation or change the characteristics of the device. For example, I may use a reactance or similar device so related to 85 the protective device as to control its action upon extreme overloads and to control and modify the effect of such overloads upon the protective device. The means for modifying or controlling the effect of overloads upon 90 the protective device may be arranged in various ways, as, for example, by connecting a reactance or similar device in shunt to the actuating winding of the protective device. The various features of my invention will be 95 more particularly described in the accompanying specification and pointed out in the appended claims.

My invention will best be understood in connection with the accompanying drawing, 100 in which merely for purposes of illustration I have shown some of the various forms in which my invention may be embodied, and in which Figure 1 is a diagram of a relay embodying one form of my invention; Fig. 105 2 is a diagram of a relay embodying another form; Fig. 3 is a diagram showing a different modification; Fig. 4 is a diagram show-

ing still another form of embodiment of my invention: Fig. 5 is a diagram showing one way of applying my invention to polyphase systems; and Fig. 6 is a diagram showing 5 an embodiment of my invention in a different type of relay.

In the particular form of electro-responsive device shown in Fig. 1, which for convenience is shown as a time limit relay, the 10 circuit breaker or other means for controlling the circuit to be protected is controlled through some suitable form of control or tripping circuit, not shown, and containing the contacts 1 which coöperate with the 15 bridging contact 2 to close the tripping circuit and thereby cause the circuit breaker to open the circuit to be protected. The movement of the contact 2 is retarded by any suitable form of retarding device 20 such as a bellows retarding device 3. The contact 2 is moved into operative engagement with the contacts 1 by any suitable movable member of the relay, such as the core 4 which moves the contact 25 2 against the resistance of the retarding device 3. An actuating coil or winding 5 moves the member or core 4 upward when energized. This actuating winding is supplied with current through an energizing 30 circuit 6 which is in any convenient way, as for example by a current transformer, supplied with current derived from the circuit to be protected. When an abnormal condition, such as an overload, for example, 35 occurs upon the circuit which is to be protected, the actuating winding 5 is energized and the member or core 4 is moved upward at a rate which is controlled by the retarding device or bellows 3. As the current in 40 the energizing circuit 6 is roughly proportional to the amount of overload on the main circuit a very severe overload or short circuit would cause the actuating winding 5 to exert a very strong pull upon the core 4 and overpower the retarding device 3 unless some suitable provision is made to 45 guard against its action.

In accordance with my invention I 50 modify and control the action of the actuating winding 5 upon the member or core 4 by some suitable means which becomes operative only when the abnormal conditions in the main circuit become so extreme that there is danger of the normal and desired 55 action of the relay being affected. I prefer to use some kind of automatic shunt which will act as a kind of safety valve or bypass for the excess current, and thus automatically shield the winding 5 from the excess current. In the particular arrangement shown in Fig. 1, I provide electro-reactive means such as the coil 7 connected in 60 shunt to the actuating winding 5 and mounted in inductive relation to a magnetic circuit or iron or other suitable material

proportioned to saturate whenever the current in the circuit to be protected reaches a value great enough to derange the protective device. As long as the magnetic circuit of the reactive winding 7 is below 70 saturation the winding exerts its full reactive effect and comparatively little current will flow through it, but as soon as the magnetic circuit saturates the reactive effect does not increase with the current, and for excess 75 current the electroreactive means acts substantially as a resistance and permits most of the excessive current to flow through it, so that the excess current is shunted or diverted from the actuating winding 5 as 80 long as the magnetic circuit of the reactive winding 7 is saturated. Although the reactance in shunt to the actuating winding 5 may be constructed in any suitable way a compact and simple device can be made as 85 shown in Fig. 1 by utilizing an iron frame 8 having a cross bar 9 and a core 10 for the magnetic circuit of the reactive winding 7 and also for part of another magnetic circuit which includes the core 4 and is energized by the actuating winding 5. By suitably proportioning or adjusting the parts 90 8, 9 and 10, there is secured for the reactive winding 7 a magnetic circuit which will saturate upon any desired amount of over- 95 load upon the circuit to be protected.

The operation of this device is as follows: When an overload appears upon the circuit to be protected current flows through the energizing circuit 6 and the actuating winding 5, whereupon the winding 5 exerts upon the member or core 4 a force approximately proportional to the amount of overload. As long as the overload on the main circuit is below a predetermined limit the magnetic 100 circuit of the reactive winding 7 is not saturated, and the reactive effects prevents any great amount of current from flowing through the winding 7. As the overload increases the amount of current in the energizing circuit 6 also increases until at a predetermined limit the magnetic circuit of the reactive winding 7 becomes saturated, whereupon it begins to modify or control the action of the winding 5 in such a way that even 105 though the overload increases far beyond the predetermined limit, nevertheless the force exerted by the winding 5 upon the member or core 4 increases only a comparatively slight amount. The result is that up to a predetermined limit the force exerted upon the movable member or core 4 is approximately directly proportional to the amount of overload, but as soon as the overload exceeds a predetermined limit an increase in overload 110 beyond that limit causes a comparatively very slight increase in the force exerted upon the member 4. As a result the retarding device 3 is able to control the movement of the member 4 under all conditions and 115

all overloads, and the time limit of the protective device is practically unaltered even on very heavy overloads.

In the modification shown in Fig. 2, the reactance is exterior to the protective device and comprises a winding 11 mounted upon a magnetic circuit 12 which is proportioned to saturate at a certain definite amount of current on the main circuit. The reactance 11 modifies or controls the action of the winding 5 in the same way as the device shown in Fig. 1.

In Fig. 3 I have shown a modification in which the action of the actuating winding 15 of the relay is modified or controlled, at least in part, through the energizing circuit 6. In this particular form of my invention the energizing circuit 6 receives its current through a transformer 13 comprising a secondary winding connected directly to the energizing circuit 6 and a primary winding supplied from the current transformer 14 which supplies current derived from the circuit to be protected. The iron core of the transformer 13 is so proportioned that when the current in the circuit to be protected reaches a certain predetermined amount the iron core is saturated. When this occurs the current in the main circuit can increase to a very great amount, yet there would be only a comparatively slight increase in the amount of current in the energizing circuit 6, since the ratio of the transformer 13 changes as soon as its core becomes saturated, and as long as the core is saturated excessive currents may flow through the primary without producing corresponding amounts of current in the energizing circuit 6.

In Fig. 4 I have shown a modification of my invention in which the energizing circuit 6 supplies current to an actuating winding 15 and also a control winding 16 connected in series with the actuating winding 15 and provided with a magnetic circuit which saturates when the current in the main circuit reaches a predetermined limit. The coils 15 and 16 are wound to oppose each other and are so related that when the magnetic circuit of the control coil 16 becomes saturated the control coil will exert a modifying or controlling effect which counteracts to a large extent the effect of the actuating coil 15. In the particular form shown the relay is made with the iron frame 8, as shown in Fig. 1, and the control coil 16 is wound upon the core 10. As in the form of device shown in Fig. 1, the magnetic circuit through the upper part of the frame 8 and the parts 9 and 10 is so proportioned that it saturates when the current in the main circuit reaches a definite limit.

The operation of this form of the device is as follows: As long as the magnetic circuit of the control coil 16 is not saturated

the lines of force generated by that coil remain in the iron and do not affect the field set up by the actuating winding 15. When the magnetic circuit of the winding 16 becomes saturated, any further increase in current will cause a stray magnetic field which counteracts or opposes the magnetic field set up by the winding 15 and consequently modifies or controls the effect of the winding 15 upon the member 4 to such an extent that even though the current in the main circuit increases very materially above the limit at which the magnetic circuit of the coil 16 became saturated, yet the force exerted upon the member or core 4 increases only a comparatively slight extent. As a result of this co-action of the windings the retarding device 3 is able to control the core under practically all conditions of overload.

To facilitate understanding of my invention, I have shown and described in the preceding figures relays which are adapted for single-phase circuits, but my invention is equally applicable to polyphase circuits. Merely for purposes of illustration I have shown diagrammatically in Fig. 5 one way of applying relays similar to the relay shown in Fig. 1 to a three phase circuit. Each phase of the circuit is provided with a relay having a current coil 5 energized by current dependent upon the current in the phase to which it is connected. Any one of the relays can control the three phase circuit through a common tripping circuit 17. In the particular arrangement shown the tripping circuit is normally open, and is supplied from some suitable local source such as storage battery 18. Whenever the tripping circuit is closed by any one of the three relays, the trip coil 19 is energized and opens the three phase circuit by means of some suitable form of switch not shown.

My invention is also applicable to many other forms of devices than relays, and may be applied equally well to any form of relay which responds to conditions upon an electric circuit. In Fig. 6 I have shown diagrammatically a disk type of relay embodying one form of my invention. In this particular figure the tripping contacts 20 are driven through suitable connections 21 from the disk 22, which is actuated by potential coils 23 and a current coil 24 in a manner which is common in watt-meters and is well understood. In accordance with my invention I modify the effect of excessive currents upon the relay by means of an automatic bypass or shunt for controlling the current coil 24, this shunt being formed of reactance 25 connected in parallel with the current coil 24 and proportioned to protect the current coil 24 from the effects of excessive currents in the circuit 26.

My invention may be embodied in many

other forms than those illustrated and described, and therefore I do not limit my invention to the precise arrangement disclosed except in so far as it is limited by the scope of the appended claims.

What I claim as new and desire to secure by Letters Patent of the United States, is:—

1. A protective device comprising a movable metallic member, retarding means for opposing movement of said member, two windings, said member being movable in response to abnormal current in one of said windings, and an iron *yoke* in inductive relation to said windings and proportioned to saturate when the current in one of said windings exceeds a predetermined limit.
2. A protective device for electric circuits comprising a retarded movable circuit controlling member, a yoke of magnetic material shaped to provide one magnetic circuit including said movable member and another distinct magnetic circuit, an actuating winding for energizing the first magnetic circuit to move said member, and a second winding in inductive relation to the other magnetic circuit and proportioned to saturate said other magnetic circuit upon the occurrence of a predetermined overload upon the circuit to be protected.
3. A protective device for electric circuits comprising an actuating winding

responsive to abnormal conditions in the circuit to be protected, a retarded circuit controlling member actuated by said winding, a second winding mounted coaxially with said actuating winding and wound to control the effect of said actuating winding upon said circuit controlling member, and a magnetic circuit in inductive relation to said second winding proportioned to saturate upon the occurrence of an overload which exceeds a predetermined value.

4. A protective device comprising a movable circuit controlling member, an iron yoke providing two magnetic circuits, an actuating winding operatively related to one of said magnetic circuits and responsive to abnormal conditions on the circuit to be protected for controlling the movement of said circuit controlling member, and a second winding operatively related to the other of said magnetic circuits for modifying the action of said actuating winding on abnormal conditions above a predetermined amount.

In witness whereof, I have hereunto set my hand this 5th day of August, 1913.

EDWARD M. HEWLETT.
